UNITED STATES PATENT OFFICE.

ISIDOR KITSEE, OF PHILADELPHIA, PENNSYLVANIA.

COLOR PHOTOGRAPHY.

1,206,000.

Specification of Letters Patent. Patented Nov. 28, 1916

Application filed April 8, 1915. Serial No. 19,969.

To all whom it may concern:

Be it known that I, ISIDOR KITSEE, a citizen of the United States, residing at 209 Walnut Place, Philadelphia, in the county 5 of Philadelphia and State of Pennsylvania, have invented certain new and useful Improvements in Color Photography, of which the following is a specification.

My invention relates to an improvement 10 in color photography and has more special reference to the method of and means for producing color-carriers and the application of same to photographic blanks.

The color-carriers of auto-chromes of to- 15 day have the following disadvantages:— First:—The particles undergo a chemical change when exposed to intense light, and as a consequence the color changes, that is, fades. Second:—The carrier itself is not 20 transparent. Third:—The sub-division is not minute enough.

The object of my invention is to overcome these difficulties, and for the purpose of assisting persons versed in the art to practice this my invention, I will enumerate 25 some examples:

Example 1: Soluble cellulose, dissolved in one of its solvents, for instance acetone or amyl acetate, the solution is colored to suit 30 requirements and is then sprayed from a comparatively great height through an atmosphere adapted to make the individual particles non-adherent and adapted to evaporate the solvent, thereby leaving the minute 35 particles in their solid state. An atmosphere of steam, not of too high a temperature, is well adapted for this purpose. A receptacle filled with a liquid adapted to further coagulate each particle is provided at 40 the lower end of the tower or tube. Water will answer the purpose.

Example 2: Gelatin is dissolved and dyed to suit requirements. This solution is then sprayed from a comparatively great 45 height through an atmosphere which coagulates each particle, and makes the same non-adherent to the next particle. A tower or tube should be employed as in Example 1, and to make the atmosphere suitable for the 50 purpose in question, I prefer to charge the air contained in said tower or tube, with fumes of formaldehyde.

It is obvious that particles of as many colors as desired, may be produced, either 55 in accordance with Example 1 or Example 2, and it is only necessary to state that the

colors to be used with celluloid, should not be soluble in water, (anilin colors are therefore preferred). Generally a three color scheme is employed in color-photography, 60 such for instance as red, yellow, blue, but for the purpose of my invention, it is immaterial if a three or four color scheme is preferred, and the colors may vary without departing from the scope of my invention. 65 After the particles carrying the different colors have been dried, they are, by preference with the aid of a revolving drum, carefully inter-mixed.

To apply the so preferred color-carriers 70 to the surface of a blank to be used later in color-photography, I prefer the following steps:—The surface of the blank is first made adhesive. If celluloid is used, a gum arabic or gelatin solution will answer the 75 purpose well. If gelatin is used, a celluloid solution may answer, but under no circumstances should the adhesive coat consist of a material in which the carrier or its color is soluble. 80

The careful and exact preparation of the blanks for the reception of the color particles is of great importance, and on it depends to a great extent the full success of the operation. The moistening of the surface of the blank with the adhesive solution, and the adhesiveness of the solution itself has to be just sufficient so that the color particles may cover the whole surface, but should not be able to retain a second particle 90 on top of the first particle; in other words, the unit of color should not be increased by a second particle of the same color or decreased through a particle of different color. When the surface of the blank is in just the 95 condition required, then the color-carriers, inter-mixed as to the different colors, are placed in a sprayer and sprayed onto the prepared surface. After a few minutes, the surplus particles are, by preference with the 100 aid of an air-sprayer, removed from the surface and the blank has to undergo a careful inspection, to ascertain if two or more particles are covering each other. In such case, it is best to remove either the upper particle 105 alone or all the particles from the particular spot, and cover the same again.

A short practice will soon advise the operator as to what density his adhesive solution should have, and the time necessary to elapse between the covering of the blank 110 with the solution, and application of the

color particles to the surface, so that the proper degree of moisture and adhesiveness is reached.

Having now described my invention, what I claim as new and desire to secure by Letters Patent is:

1. The method of producing color carriers for auto-chrome blanks, which consists in first dissolving a suitable solid in a liquid, 10 dyeing that liquid with a suitable color, spraying the colored liquid through a gaseous atmosphere adapted to produce a non-adherence between the different particles, drying the different particles, producing 15 such particles of as many colors as required, and inter-mixing the particles of different colors.

2. The method of producing auto-chrome blanks which consists in first producing the 20 different color carriers through the process of spraying the color solutions, each separately, through an atmosphere surcharged with a chemical agent adapted to make the different particles non-adherent, then inter- 25 mixing the different colored particles and cementing the same onto the blank adapted to be used for an auto-chrome.

3. In the production of color carriers for 30 autochrome blanks the step which consists in first dissolving a suitable solid coagulable by formaldehyde in a suitable liquid, coloring the same with a suitable color and then

spraying the same through an atmosphere surcharged with formaldehyde.

4. In the art of producing color screens 35 for photographic blanks the method which consists in first dissolving suitable solid substances coagulable by formaldehyde in suitable liquids, dyeing said dissolved substances in the required colors, spraying the so-colored liquids, each separately through an atmosphere containing formaldehyde, thereby 40 producing minute colored particles and then cementing said particles onto a blank adapted to be used for photographic purposes. 45

5. In the art of producing color screens for photographic blanks the steps as follows: dissolving a suitable substance with the aid of a suitable liquid, dividing said liquid into separate parts, coloring each 50 part separately, spraying each of the divided liquids through an atmosphere charged with a gaseous agent adapted to congeal said liquids into minute parts thereby producing minute colored carriers, drying said 55 carriers and cementing the same on a suitable base adapted for photographic purposes.

In testimony whereof I affix my signature in presence of two witnesses.

ISIDOR KITSEE.
